Technical drawing of a mechanical device, likely a valve or pump, showing internal components and external parts labeled with numbers 1 through 38. The drawing is a cross-sectional view with various parts labeled as follows:

- 1, 6, 7: Internal components at the top left.
- 10, 11, 12, 13, 14, 15, 16, 17, 18, 19, 20, 21, 22, 23, 24, 25, 26, 27, 28, 29, 30, 31, 32, 33, 34, 35, 36, 37, 38, 39: Various numbered parts throughout the assembly.

APPARATUS FOR SEALING TINS, CANIS-
TERS, JARS, AND THE LIKE UNDER VACU-
UM

Oscar Legg, Sunbury-on-Thames, England

Application May 7, 1940, Serial No. 333,722
In Great Britain May 18, 1939

1 Claim. (Cl. 226—82)

This invention relates to vacuum sealing apparatus for securing covers on containers under vacuum. It has already been proposed to provide apparatus of this type comprising a vacuum chamber into which a plurality of containers with their covers loosely in position are inserted through a suitable opening in one side after which the opening is hermetically sealed by a suitable door and a vacuum produced in the chamber and consequently in the containers. Pressure is then applied to the covers by causing a relative movement between the containers and a pressure plate arranged above them in the chamber. Finally air or gas is admitted into the chamber so that the covers are hermetically sealed on the containers by atmospheric pressure, the containers are relieved from the pressure of the pressure plate, the door opened and the containers removed from the chamber.

In order to save time it has been found preferable to provide openings in opposite sides of the chamber so that a batch of containers can be removed from one side while a fresh batch is being inserted in the opposite side. In apparatus of this type which has been employed heretofore, the doors for the openings have been mounted so that they can be moved simultaneously transversely across the open ends of the chamber between a position in alignment with the openings and a position clear of the openings and means have been provided for moving first one door and then the other in a direction normal to the plane of the openings to bring them into and out of sealing position, said means being operated from the two opposite sides of the apparatus thus making it necessary for the operator to move from one side of the apparatus to the other to seal and unseal the doors, while means for controlling the vacuum in the chamber and the pressure applied to the covers of the containers have been arranged at the front of the apparatus. Consequently a considerable amount of time has been required to effect the several operations.

The object of the present invention is to provide improved apparatus of the abovementioned type having simple and reliable means for controlling the movements of the doors, the producing of the vacuum in the chamber and the application of pressure on the covers of the containers from a single position.

A further object of the invention is to provide an apparatus which is of robust construction and is reliable in operation.

In the accompanying drawings Figure 1 is a front elevation of a preferred form of apparatus

constructed in accordance with my invention and Figure 2 is a side elevation of the apparatus. Figures 3, 4 and 5 are detail views showing the valve and the connections to it controlling the final closing of the doors and the evacuation of the vacuum chamber. Figure 6 is a detail view of the release valve of the hydraulic jack.

The apparatus shown in the drawings comprises a vacuum chamber having a front wall 1, back wall 2, top 3 and bottom 4. The opposite sides of the chamber are open and are arranged to be hermetically closed by doors 5 and 6. The doors are provided with outwardly projecting studs 7 which are fitted to slide in holes in arms 8 secured on the opposite ends of a shaft 9 which is journalled across the back of the vacuum chamber on the frame 10 which supports the apparatus. Weights 11 are secured to the shaft 9 to counterbalance the doors so that they can be moved easily in a direction transverse to the openings in the sides of the chamber by means of a handle 12 projecting from one of the arms 8 to a position which is readily accessible at the front of the apparatus. Springs 13 are arranged on the studs 7 to bias the doors 5 and 6 away from the open sides of the vacuum chamber so that they can move freely across the openings between a position clear of the openings and a position in alignment with them.

Each door 5 and 6 is provided with a pair of catch plates 14 and 15, one at the top and one at the bottom and each catch plate is provided with a notch 16 arranged to engage behind a head 17 on a piston rod 18 projecting from a piston arranged to reciprocate in a cylinder 19. The cylinders 19 are secured on the outside of the chamber in such a position that the piston rods engage in the notches 16 and act as stops to hold the doors in correct alignment with the openings which they are to seal. The cylinders on the top of the chamber are set back so that the heads 17 do not project into the transverse path of movement of the doors and the upper catch plates 14 are cranked inwards as shown at 20 to enable the notches 16 in them to engage the piston rods 18 behind the heads 17.

The vacuum chamber is connected with any suitable vacuum means by a suction pipe 21 having a control valve 22 operated by a rod 23 which is mounted to extend to the front of the chamber where it is provided with an operating wheel 24. The control valve comprises a valve casing provided with a peripheral port 22a communicating with the cylinders 19 through pipes 25, a peripheral port 22b communicating with the vacuum

chamber and a peripheral port 22c communicating through a branch 22d with the atmosphere or a source of pressure gas. Fitted into the casting is a rotatable cylindrical valve member which is coaxial and rigid with the rod 23 and forms a continuation of the pipe 22 leading to the vacuum means. Thus, the space enclosed by the rotatable valve member is in constant direct communication with the vacuum means. The valve member is provided with two peripheral ports 24a and 24b spaced 90° from each other.

When the valve member is turned to the position shown in Fig. 3, the opening 24a registers with the port 22a and a vacuum is produced in the cylinders 19 to draw the pistons inward before the vacuum chamber is connected to the vacuum means. The inward movement of the piston rods 18 draws the doors inwards to hermetically close the openings in the sides of the chamber, for which purpose the doors are preferably provided with strips of packing inserted in grooves on their inner faces as indicated at 26 in Fig. 2. The wheel 24 is then given a further turn through 90° to the position shown in Fig. 4 to connect the vacuum chamber with the vacuum means. As will be seen from Fig. 4, in this position of the valve, the opening 24b registers with the port 22b.

A platform 27 for supporting the containers to be sealed is arranged to be reciprocated vertically in the vacuum chamber. This platform 27 is mounted on the upper end of a piston rod 28 which is fitted to slide in an air tight manner through an opening in the bottom 4 of the chamber. The lower end of the piston rod 28 is connected to a piston mounted to reciprocate in a cylinder 29 to which fluid under pressure is supplied by a pump 30 operated by an electric motor 31 mounted on the frame 10 beneath the vacuum chamber. The supply of fluid to the cylinder 29 below the piston to raise the platform 27 is controlled by a release valve 32 connected by links 33 and a rod 34 with an operating handle 35 on the front of the apparatus. A vacuum gauge 36 and a pressure gauge 37 are mounted on the front of the apparatus and an inspection window 38 is provided in the front wall of the vacuum chamber. The release valve 32 is of known construction and does not form a part of the present invention. When this valve is opened, it permits escape of the pressure fluid below the piston in cylinder 29, and the weight of the platform 27 is then sufficient to press the piston down.

The operation of the apparatus is as follows: The containers with their covers loosely in place are preferably arranged on trays of a convenient size to pass through the open sides of the vacuum chamber. The operator opens the doors 5 and 6 simultaneously by raising the handle 12. A tray containing a charge of containers is inserted through one side opening on to the platform 27 and the doors brought into alignment with the openings by pulling the handle down until the notches 16 engage the piston rods 18 behind the heads 17. The wheel 24 is then turned to bring the valve member to the position shown in Figure 3 whereupon the cylinders 19 are connected with the vacuum means through the ports 22a, 24a. As a result, the piston rods are drawn inwards so that the heads 17 act on the catch plates 14 and 15 to move the doors 5

and 6 inwards in a direction normal to the planes on the sides of the vacuum chamber to seal the openings. The turning of the wheel 24 is continued until the vacuum chamber is connected with the vacuum means, as shown in Figure 4, through ports 22b, 24b to produce a vacuum in the chamber and consequently in the containers in the chamber. The handle 35 is then turned to close the release valve 32 and admit fluid through the valve 32 into the cylinder 29 beneath the piston to raise the platform 27 with the containers until the covers are pressed against the top of the chamber to press them firmly into sealing position on the containers. The wheel 24 is then turned to the position shown in Figure 5 to admit air or gas into the chamber through ports 22c, 24b, 24a, 22b and thereafter, through a further 90° to admit air to the cylinders 19 through ports 22c, 24a, 24b, 22a in order to release the doors 5 and 6. The springs 13 on the studs 7 draw the doors away from the openings when they are released and if desired springs may also be arranged behind the pistons in the cylinders 19 to press the piston rods 18 outwards to keep them from opposing the action of the springs 13. After the doors have been released the handle 35 is turned to open the release valve and permit fluid to escape from the lower part of the cylinder 29 to lower the platform 27; the doors 5 and 6 are then moved transversely away from the openings by raising the handle 12, the containers are removed from the opening at one side and a fresh charge of containers inserted at the opposite side. The trays carrying the containers may be conveyed to the opening at one side and carried away from the opening at the other side by conveyor belts or any other suitable means.

The gauge 37 indicates the pressure applied to the covers by the action of the pump 30 and the cylinder is provided with the usual regulating valve for adjusting this pressure. The vacuum gauge 36 indicates the degree of vacuum produced in the vacuum chamber.

What I claim is:

In an apparatus for sealing covers on containers under vacuum, the combination of a vacuum chamber having openings at opposite sides and a suction pipe connecting said chamber to vacuum means, a shaft journaled on the outside of the chamber, arms mounted on the opposite ends of said shaft, doors carried by said arms, means for rocking said shaft to move the doors transversely into and out of alignment with the said openings, cylinders mounted on the apparatus, piston rods projecting from pistons mounted to reciprocate in said cylinders, shoulders on the outer ends of said piston rods, latch plates carried by the doors in position to engage behind said shoulders on said piston rods when the doors are in alignment with the said openings, connections from the said cylinders to the said vacuum means for producing a vacuum in the cylinders to cause the piston rods to move the doors to sealing position, at least one movable pressure member in said vacuum chamber, operating means for producing a movement of said pressure member to press the covers onto the containers and control means arranged in positions accessible from the front of the apparatus for controlling the movements of the doors, the movement of the said pressure member and the evacuation of the chamber.

OSCAR LEGG.
